Primary Examiner — Manpreet Matharu*Assistant Examiner* — Mojtaba Tehrani(74) *Attorney, Agent, or Firm* — Jenkins, Wilson, Taylor & Hunt, P.A.(57) **CLAIM**

The ornamental design for compact chiller and condenser, as shown and described.

DESCRIPTION

FIG. 1 is a front perspective view of a compact chiller and condenser, showing our new design;
 FIG. 2 is a front elevation view thereof;
 FIG. 3 is a rear elevation view thereof;
 FIG. 4 is a top plan view thereof;
 FIG. 5 is a bottom plan view thereof;
 FIG. 6 is a left side elevation thereof; and,
 FIG. 7 is a right side elevation view thereof.
 The broken line in the figure drawings represents unclaimed environment only and forms no part of the claimed design.

1 Claim, 6 Drawing Sheets(56)
